UNITED STATES PATENT OFFICE.

EPHRAIM VIERTELS, OF NEW YORK, N. Y.

TIP-FASTENER FOR SHOE-LACES.

1,327,892.

Specification of Letters Patent. Patented Jan. 13, 1920.

Application filed August 23, 1918. Serial No. 251,084.

To all whom it may concern:

Be it known that I, EPHRAIM VIERTELS, a citizen of the United States, residing at the city of New York, in the county of Bronx 5 and State of New York, have invented certain new and useful Improvements in Tip-Fasteners for Shoe-Laces, of which the following is a specification.

My invention relates to a tip fastener 10 for shoe laces. Devices of this character are old and well-known, and more particularly are shown in U. S. Patent No. 1,231,103 dated June 25, 1917.

Such devices are intended to put on new 15 tips on shoe laces, from which the original tips have been twisted off, and are usually operated by hand.

Prior devices of this character have been 20 expensive to manufacture, as they depended upon movable dies which had to be accurately made and fitted together, so that a good deal of hand work was necessary in their construction. In addition these former devices were not always reliable in their 25 operation.

According to my present invention, a very 30 cheap and efficient apparatus is provided which does not require any especial skill or hand work either in its construction or in the assembling of its parts.

Other objects of my invention will be mentioned in the following description and drawings which illustrate a preferred embodiment of my invention.

35 Figure 1 is an elevation of my device. Fig. 2 is a top view thereof.

Fig. 3 is an elevation with the front plate removed, and on a larger scale.

Fig. 4 is a section on the line 4—4 of 40 Fig. 3.

Fig. 5 is an elevation of two intermeshing die members.

Fig. 6 is a view similar to that of Fig. 5, showing the die members reversed.

45 Fig. 7 shows a shoe lace and a metal blank intended to be affixed thereto.

Fig. 8 shows the shoe lace and the metal tip affixed thereto.

Two scissor-like members 1 and 2 are pivoted at 3, and have upper portions 8 and 9, which are of equal width. These scissor-like members or limbs 1 and 2 have projec-

tions 4 and 5 with a spiral spring 7 secured thereto, so that the spring 7 always tends to force the limbs 1 and 2 together and maintain the die members in the position shown in Figs. 3 and 4, in which the opposite die members intermesh. It is not necessary that these opposite die members should intermesh but this is preferred. Projections 41 and 5 55 have lugs 6 connected thereto, and fitting into spring 7, for the purpose of maintaining its proper alinement.

The plates 8 and 9 are provided at their middle line with projections 18, to which 60 cutting members 21 and 20 are secured by rivets 19 or other suitable means, so that the end of the shoe lace can be trimmed if desired.

The bodies of the members 8 and 9 are 70 suitably hollowed to receive a series of die members 6 and 7. These die members 6 and 7 are made of steel or other material which permits their being stamped into the desired shape, so that all molding and castings 75 are obviated. These die members 6 and 7 are arranged in two series, each of the parts 8 and 9 which may be called die supports, receiving and holding one of these series. In each of these series the die members 6 and 80 7 alternate and a die member 6 in one series is directly opposite to a die member 7 in the other series, so that each die member 6 intermeshes with an opposite die member 7 in the opposite series. It will be noted that each 85 die member 6 is provided with two teeth 33 separated by wedge-shaped depression 32 and that the die members 7 are provided with the hollows 30 which have the same contour as the teeth 33 and are also provided 90 with a central part having a contour corresponding to that of the depression 32. The central parts of the die members 7 have arcuate depressions 31, which coöperate with the wedge-shaped depressions 32 to crimp and 95 force together the edges of the metal blanks 23, which form the tips of the shoe laces.

Each die member connected to one support, as seen in the drawings, is directly opposite the opposite die member connected to the other support, so that their centers are located in and move in the same plane.

As seen in Figs. 2 and 4, the die support 8 has plates 10 and 11 secured thereto by

means of bolt 12, which passes through the holes 15 and 16 in the die members 6 and 7, and clamps them firmly together so that they operate as though they were integral with each other. The series of die members connected to the die support 9, are secured thereto by means of the bolt 4, which passes through the holes 15 and 16 of the die members 6 and 7 to which it is connected and 10 also clamps them firmly together. The plate 11 has an opening 17, which is directly in line with the space between the arcuate depressions 31 and the inner ends of the wedge-shaped depressions 32 so that if blank 23 is 15 thrust through the opening 17, it fits between the face of these depressions, which act exactly like the face of a die of the well-known type that is used for clamping these metal blanks 23 to the shoe lace 22.

20 The operation of my device is as follows:

When the tip of the shoe lace has fallen off the end thereof, it is trimmed off by means of the cutting members 20 and 21. 25 Then a blank 23 is fitted over the end of the shoe lace and the shoe lace with the blank fitting over its end is inserted between the depressions 31 and the inner ends of the depressions 32. Upon forcing the 30 limbs 1 and 2 toward each other the blanks 23 are bent so that their edges overlap, and they are then powerfully compressed upon the shoe lace so as to firmly grip it. Upon releasing the pressure upon the limbs 1 and 35 2, they are forced apart by the spring 7 and the retipped shoe lace can now be withdrawn.

Although the drawings illustrate the ordinary cylindrical form of shoe lace tip it is 40 one of the marked advantages of this construction that by stamping out die members 6 and 7 to a suitable shape, a conical, corrugated, or other form of shoe lace tip may be affixed, and the die members for different 45 shapes of tips can be readily inserted into the die supports 8 and 9, as the bolts 4 and 12 can be readily made detachable.

I have here shown the dies as made of a series of laminations made of sheet metal 50 but dies cast in one piece, and having the characteristics before mentioned, would be fully an equivalent thereof.

I have illustrated a preferred embodiment of my invention but it is clear that numerous 55 changes and omissions could be made in its details without departing from its spirit.

What I claim is:

1. In a device for tipping shoelaces, die supports, dies secured to the said die supports, the said dies being composed of a series 60 of spaced sheet metal laminations, means for connecting the said laminations to said supports, so that a lamination connected to one support is directly opposite an opposite 65 lamination connected to the other support,

and means for increasing and decreasing the distance between said dies, the opposed surfaces of said dies being adapted to close a metal blank on the end of a shoelace and clamp it to the said end thereof. 70

2. In combination, die supports, means for moving these die supports toward and from each other, and dies connected to the said die supports, the said dies being composed of a series of laminations, each said 75 series comprising alternating members of two species, the members of one of said species having upper and lower depressions with intermediate projections having arcuate points, and the members of 80 the other of the said species having lower and upper teeth adapted to fit into the said upper and lower depressions, and having recesses intermediate the said upper and lower teeth, the walls of the said recesses being adapted to coöperate with the walls of the said projections, to form die-surfaces 85 for clamping a blank on the end of a shoe lace, the members of one species in one of the said dies being opposite members of the 90 other of the said species in the other of the said dies.

3. In combination, die supports, means for moving said die supports toward and from each other, dies carried by the said 95 supports, the said dies being composed of a series of laminations, each said series comprising alternating members of two species, the members of one of said species having upper and lower depressions with intermediate projections having arcuate points, and the members of the other of the said species having lower and upper teeth adapted to fit into the said upper and lower depressions, and having recesses intermediate the said 100 upper and lower teeth, the walls of the said recesses being adapted to coöperate with the walls of the said projections, to form die-surfaces for clamping a blank on the end of a shoe lace, the members of one species in 110 one of the said dies being opposite members of the other of the said species in the other of the said dies, the said members having aligned perforations and bolts passing through the said perforations and rigidly 115 clamping the said members together and to the said supports.

4. In combination, a pair of pivoted limbs, the ends of said limbs on one side of said pivot being adapted to act as die-supports, dies carried by the said supports, the said 120 dies being composed of a series of laminations, each said series comprising alternating members of two species, the members of one of said species having upper and lower 125 depressions with intermediate projections having arcuate points, and the members of the other of the said species having lower and upper teeth, the walls of the said recesses being adapted to coöperate with the 130

walls of the said projections, to form die-surfaces for clamping a blank on the end of a shoe lace, the members of one species in one of the said dies being opposite members of the other of the said species in the other of the said dies, the curvature of the said depressions and the said teeth being such

that the said teeth are adapted to move in and out of the said depressions, when the said limbs are revolved about the said pivot. 10

In testimony whereof I hereunto affix my signature.

EPHRAIM VIERTELS.
